his Attorney

UNITED STATES PATENT OFFICE.

VALENTINE A. HOBART, OF SPOKANE, WASHINGTON.

SIZE-STICK.

1,283,409.

Specification of Letters Patent.

Patented Oct. 29, 1918.

Application filed January 26, 1918. Serial No. 213,951.

To all whom it may concern:

Be it known that I, VALENTINE A. HOBART, a citizen of the United States, and a resident of Spokane, in the county of Spokane 5 and State of Washington, have invented certain new and useful Improvements in Size-Sticks, of which the following is a specification.

The present invention relates to a measuring device for application to shoes for use by salesmen in fitting shoes to customers, and for similar uses.

An object of the present invention is to provide a size stick of this character which 15 is collapsible and may be folded into relatively small space and placed in the pocket; a size stick which may be readily set up for quick adjustment to the foot; a size stick which comprises relatively few parts 20 substantially constructed and assembled; to provide a size stick which may be economically manufactured.

Various other objects and advantages of this invention will be in part described, and 25 in part understood, from the following detailed description of the present preferred embodiment, the same being illustrated in the accompanying drawing, wherein:

Figure 1 is a side elevation of a size stick 30 constructed according to the present invention and set up for use.

Fig. 2 is a horizontal section taken longitudinally through the same.

Fig. 3 is a top plan view of the size stick.

Fig. 4 is a longitudinal section taken 35 through the size stick on a vertical plane, and showing the same collapsed.

Fig. 5 is an inner end elevation of the size stick showing the heel engaging end 40 thereof.

Fig. 6 is a vertical transverse section taken through the outer end of the adjustable member of the device.

Referring to this drawing, the body part 45 comprises a number of telescoping tubes, such as 10, 11 and 12 shown in the present instance, the tubes being preferably of hollow metallic construction, and being non-circular in contour to prevent the relative 50 axial turning of the sections. The sections 11 and 12 are preferably slightly flared at their ends 13 to interlock in the correspondingly reduced ends of the sections 10 and 11 when the tubes are assembled.

The inner tube 10, or the tube which is 55 adapted to engage beneath the heel of the

foot, is provided upon its inner extremity with a strap 14 encircling the tube 10 and having its end portion projecting upwardly at opposite sides of the tube to form ears 15. 60 An arm or rest 16 is pivotally mounted at its lower end between the ears 15 on a pin 17 which extends transversely through the ears 15 and supports the arm 16 for pivotal movement in the vertical longitudinal plane 65 of the body part. The lower or shorter end of the arm 16 is provided with a transverse pin or stud 18 adapted to enter an arcuate groove 19 formed in the rear edge of each ear 15. The groove 19 of each ear 15 terminates at its lower end in a vertical plane 70 of the pivot pin 17 and is adapted to retain the adjacent stud 18 from further forward movement and hold the arm 16 in right angular relation with respect to the tube 75 section 10.

A shiftable arm or contact member 20 is mounted to slide longitudinally upon the body part, said arm 20 being pivoted upon a transverse pin 21 which is secured through 80 the upstanding ears 22 which rise from a sleeve 23 surrounding the body part. The sleeve or collar 23 is of a size sufficient to receive the tube 12 therein, and the lower or short end of the arm 20 has seated therein 85 a resilient cushioning or yielding block 24 adapted to contact with the upper edge portion of the body part between the ears 22 and take up inequalities in the space between the arm 20 and the upper surface of the body 90 part incident to the variations in the thicknesses of the tubes.

The collar or sleeve 23 is secured upon the inner end of the tube section 10 by means of transverse rivets 25 which also forms 95 stops to engage the inner ends of the tube sections 11 and 12 and retain the latter from accidental displacement from the tube section 10. The upper faces of the tube sections 10, 11 and 12 are preferably flat, and 100 are provided from end to end of the body part with a graduated scale. The upstanding ears 22 of the shiftable collar 23 are provided in their outer edges with arcuate slots 26 into which transverse studs 27 fit, the 105 studs 27 being carried upon the inner short end of the arm 20 and adapted to limit the upward swinging of the arm and retain it in substantially right angular relation with respect to the body portion.

If desired, the shiftable sleeve 23 may be provided with tension springs or fingers 28

which yieldingly project inwardly against the opposite side portions of the tubes and center the sleeve 23 thereon. It will be noted that the outer ends of the tube sections 10 and 11 are gradually reduced to provide inclined surfaces over which the sleeve 23 may slide without binding or catching, and the spring fingers 28 are preferably out-turned at their free ends to form rounded bearing surfaces for engaging over the extremities of the tube sections. The resilient pad 24 is adapted to yieldingly hold the shiftable member in adjusted position so as to retain the latter in its correct relation on the body portion with respect to the graduations.

As shown in Fig. 3, the graduations are preferably divided into a scale of small sizes, such as 1 to 13 as shown at 29, and the outer end of the body portion is preferably provided with a scale of graduations indicating larger sizes, as indicated at 30. From Fig. 4, it will be noted that it is preferable to construct the slideable tube sections 11 and 12 of greater length than the inner section 10 so that when the sections are collapsed together, the sections 11 and 12 may be readily grasped by the fingers for extending the device.

In use, it is only necessary to raise the arms 16 and 20 into upstanding position, as shown in Fig. 1. The first slideable section 11 may be drawn out to its full extent, and if the body portion is not of sufficient length to afford the proper adjustment of the shiftable arm or member 20, the outer end section 12 may be grasped and extended through the intermediate section. The sleeve or slide 23 is now shifted along the body portion into contact with the end of the foot and the resilient pad 24 is adapted to retain the shiftable element in adjusted position.

When it is desired to close up the device for placing in the pocket or the like, it is only necessary to collapse the tube sections 11 and 12 within the section 10 and to slide the sleeve 23 over the tube sections into close proximity to the fixed arm 16. The arms 16 and 20 are now swung down against the upper face of the body portion when the device is relatively compact and may be easily slipped into the pocket.

It is of course understood that various changes and modifications may be made in the details of construction and design of the above specifically described form of this invention, without departing from the spirit thereof, such changes and modifications being restricted only by the scope of the following claims.

60 1. I claim:

1. In a size stick for measuring shoes, the combination of a body, a foot engaging element carried at one end of the body, a collar slidably mounted upon the body part, a second foot engaging element pivotally carried

by said collar, and a cushioning block carried upon said second engaging element and adapted to bind against the body portion and retain the second element in longitudinally adjusted position thereon.

70

2. In a size stick, for measuring shoes, the combination of a body, a foot engaging element carried at one end of the body, a collar slidably mounted upon the body, a second foot engaging element pivotally carried by 75 said collar, and relatively flat springs carried by said collar and yieldably engaging said body.

3. In a size stick for measuring shoes, the combination of a body comprising a plurality of telescopically connected sections, a foot engaging element rising from one end of the body and adapted to be folded down against the body, a collar slidably mounted upon said body, a second foot engaging element pivotally carried by said collar, and a cushioning block carried upon said second engaging element and adapted to bind against the body and retain the second element in longitudinally adjusted position 90 thereon.

80

4. In a size stick for measuring shoes, the combination of a body composed of a plurality of telescopically connected sections, a foot engaging element carried at one end of the body, a collar slidably mounted upon the body, a second foot engaging element pivotally carried by said collar, relatively flat springs carried by said collar and yieldably engaging said body to provide a sliding connection between the collar and the telescoping sections of the body.

95

5. In a size stick for measuring shoes, the combination of an elongated body portion comprising a plurality of telescoping tubes, a collar fixed to one end of the body portion and having upstanding ears, a fixed arm pivoted between the ears, co-operating means carried upon the arm and the ears for retaining the arms in upright position when raised, a sleeve slideable over the body portion and over the various sections thereof, an arm pivotally mounted upon the sleeve and adapted to be swung down against the body portion, and means for yieldingly retaining the arm in raised position.

110

6. In a size stick for measuring feet, the combination of a body portion comprising a plurality of telescoping tubes having a longitudinal row of graduations thereon, a stationary foot engaging element pivotally mounted upon one end of the body portion and adapted to be swung down against the body portion, means for holding said element in raised position when swung up from 120 the body portion, a shiftable collar adapted for movement over all of the sections of the body portion, a second engaging element pivotally mounted upon the shiftable sleeve and adapted to be swung up into parallel- 125 130

ism with the first mentioned engaging element, and a cushioning block carried upon said second engaging element and adapted to bind against the body portion and retain 5 the second element in longitudinally adjusted position thereon.

7. In a size stick for measuring shoes, the combination of an elongated collapsible body part, a foot engaging element pivotally 10 mounted upon one end of the body part and adapted to be swung up therefrom into position for engaging one end of the foot, a sleeve slidably mounted upon said body part and adapted for movement toward and 15 from the fixed engaging member, and a second foot engaging element pivotally mounted upon said sleeve and adapted to be raised therefrom for engaging with the foot, and adapted to yieldingly bind against the body 20 portion for retaining the sleeve in adjusted position.

8. In a size stick for measuring shoes, the combination of a body, a foot engaging element carried at one end of the body, a collar 25 slidably mounted upon the body, a second foot engaging element pivotally carried by said collar, a cushioning block carried upon said second engaging element and adapted to bind against the body portion 30 and retain the second element in longitudinally adjusted positions thereon, and relatively flat springs carried by said collar and yieldably engaging said body.

9. In a size stick for measuring shoes, the 35 combination of a body, a collar rigidly carried at one end of the body, a second collar slidably carried by the body, upstanding ears formed upon said second-named collar, foot 40 engaging elements pivotally connected to said ears and provided with arcuate grooves leading upwardly from their edges, and pins carried by said ears and engaging in said grooves to hold said foot engaging elements at right angles to the body.

45 10. In a size stick for measuring shoes, the combination of a body, a collar rigidly carried at one end of the body, a second collar slidably carried by the body, relatively flat springs carried by said second collar for 50 yieldable engagement with the body, up-

standing ears formed upon said collar, foot engaging elements pivotally connected to said ears and provided with arcuate grooves leading inwardly from one of their edges, and pins carried by said ears and engaging in said grooves to hold said foot engaging elements at right angles to the body.

11. In a size stick for measuring shoes, the combination of a body, a collar rigidly carried at one end of the body, a second collar slidably carried by the body, upstanding ears formed upon said collars, foot engaging elements pivotally connected to said ears and provided with arcuate grooves leading inwardly from one of their edges, pins carried by said ears and engaging in said grooves to hold said foot engaging elements at right angles to the body, and a cushioning block carried upon the foot engaging elements pivotally carried by said 60 second collar and adapted to bind against the body portion and retain the foot engaging elements which is carried by the second collar in longitudinally adjusted positions 65 upon the body.

12. In a size stick for measuring shoes, the combination of a body comprising a plurality of telescopically connected sections, a collar rigidly carried at one end of the body, a second collar slidably carried by the body, relatively flat springs carried by said second collar and yieldably engaging said body to maintain a firm sliding connection between the second collar and the various sections of the body, upstanding 80 ears formed upon said collars, foot engaging elements pivotally connected to said ears and provided with arcuate grooves leading inwardly from one of their edges, pins carried by said ears and engaging in said 85 grooves to hold said foot engaging elements at right angles to the body, and a cushioning block carried upon the foot engaging elements which is pivotally connected to the second collar, said cushioning block adapted to bind against the body portion and retain the sliding collar in longitudinally adjusted 90 positions upon the body.
